C. A. SIMPSON

PREVENTION OF OVERHEATING OF IRONS AND OTHER ELECTRICALLY HEATED APPLIANCES

Filed March 3, 1923

UNITED STATES PATENT OFFICE.

CHARLES ADAMS SIMPSON, OF CHRISTCHURCH, NEW ZEALAND.

PREVENTION OF OVERHEATING OF IRONS AND OTHER ELECTRICALLY-HEATED APPLIANCES.

Application filed March 3, 1923. Serial No. 622,511.

To all whom it may concern:

Be it known that I, CHARLES ADAMS SIMPSON, a British subject, a resident of 241 Lincoln Road, Christchurch, in the Dominion of New Zealand, have invented a new and useful Improvement Relating to the Prevention of Overheating of Irons and Other Electrically-Heated Appliances, of which the following is a specification.

10 This invention relates to electric irons and other electrically heated appliances and refers more particularly to means whereby the circuit supplying current to the heating elements of such appliances may be automatically opened upon the temperature of such appliances rising to a predetermined degree, the object of the present invention being to provide novel and effective means for this purpose, the said means being such that in 20 addition to their embodiment in new constructions, they may be simply and conveniently applied to the conversion of existing appliances.

In carrying the invention into effect the 25 means employed comprise a magnetic cut-out adapted to operate automatically to open the controlled circuit when the current therein exceeds a predetermined limit, the special feature of this device residing in manually 30 operable means for closing or replacing the switch of the cut-out, such means being so contrived that when operating the switch they will serve also to break the circuit, in other words the said circuit will be incomplete when the said means occupy that 35 position in which they are operative to close the switch of the cut-out, thus precluding the use of such manual means for the purpose of maintaining the circuit closed when the current therein is such as to cause the cut-out to 40 operate in the proper manner.

The invention includes also contacts thermostatically controlled by the temperature of the heating appliance and adapted upon 45 the temperature of the latter rising to a predetermined degree, to short-circuit the heating element of such appliance. The resistance of the circuit being reduced in this manner, the current flowing therein will correspondingly increase thereby causing the 50 cut-out to operate and open such circuit.

In order that the nature of the invention may be clearly understood, it will now be particularly described with reference to the 55 accompanying drawings, in which:

Fig. 1. shows the exterior of a cut-out constructed in accordance with the present invention.

Fig. 2. shows the interior of the same.

Fig. 3. is a sectional elevation of the same 60 along the line A—B Fig. 2.

Fig. 4. is a plan view of the rear portion of an iron equipped in accordance with the invention, and

Fig. 5. is a diagram of the wiring employed in connection with the invention.

As here shown, 1 is an iron or other electrical heating appliance, which for simplicity will be hereinafter referred to in this description as "the iron" and 2 are the circuit wires or conductors whereby current from a suitable source is supplied to the heating element 3 of the iron.

Inserted in series in the said circuit 2 is a switch of any suitable form such as that here shown consisting of a blade 4 adapted to close with a contact 5 for the purpose of completing the said circuit.

The said blade 4 is adapted to be turned to disconnect with the contact 5 by means of a magnetically operable device having its winding included in series in the said circuit and which device is adapted when energized to the required extent to operate the said switch either directly or through suitable intermediate mechanism.

In the preferred form of the construction this magnetic device consists of a solenoid coil 6 arranged with its axis vertical and beneath the blade 4, such coil being provided with the usual iron core 7, having at its upper end a rod or extension 8 of non-magnetic material. The core 7 normally occupies its lower position within the coil as here shown but upon such coil becoming energized to the required extent the said core will be drawn upward thereby causing its extension 8 to strike and open the switch. The said coil which may consist of one or more layers of winding is preferably encased in iron, as here shown, in order to increase its effective action upon the core.

In the preferred form of the construction provision is made for adjusting the normal position of the core in order that by raising or lowering such position the device may, within limits, be set to operate at any desired current. This means of adjustment may conveniently take the form here shown and consisting of a set-screw 9 tapped 105

through a plate or other fixture at the lower end of the coil, so that the point of such screw will serve as a rest for the core 7.

According to the present invention for the purpose of closing the blade 4 with its contact 5 there is provided a manually operable device adapted when closing the said switch to also break the circuit in which such switch is contained.

10 In the preferred form of the construction as here shown this device takes the form of a knob or handle 10 which is keyed upon a spindle 11 and to which latter is keyed also an arm or crank 12 which normally occupies the upward position here shown in full lines but is capable of being turned by means of the knob 10 into the dotted line position for the purpose of closing the switch. Pivoted upon the spindle 11 is a 15 second arm 13 which is connected with the said arm 12 by means of a spring 14, the arrangement being such that while the arm 12 is in its normal or inoperative position the spring 14 will cause the arm to bear 20 against a pin or contact 15 so as to make electrical connection therewith, but as the arm 12 is turned into its operative position the spring will thereby be carried into such a position as to cause it to exercise its control 25 of the arm 13 upon the other or opposite side of the pivotal point of the latter with the result that such arm 13 will instantly leave the contact 15 and turn in a downward direction until arrested by a 30 limiting stop 16. If so desired the arm 13 may take the form of a switch-blade and the contact 15 may be a spring-contact similar to the contact 5 to receive such blade. A suitable spring 17 is preferably provided 35 to restore the arm 12 and its knob 10 to their normal positions after each manipulation.

The said arm 13 and contact 15 are inserted in series in the circuit 2 that is to say a break is formed in such circuit and the wire at one side of such break is connected to the arm 13 in any suitable manner as by connecting it to a metallic bush or bearing in which the spindle 11 turns while 45 the wire at the other side of such break is connected to the contact 15.

The said mechanism of the cut-out is enclosed in a suitable case 18 from the exterior of which projects the knob 10.

50 The iron is provided with thermostatic means arranged within the thermal influence of the heating element, such thermostatic means consisting preferably of a bimetallic strip 26 adapted to bend or become distorted in response to variations of temperature. The said strip is provided with or adapted to control an electric contact 19 arranged to co-operate with a stationary contact 20, the arrangement being such that 55 while the temperature of the iron remains

below a predetermined degree the said contacts will lie apart, but upon the temperature exceeding a predetermined degree the contact 19 will make electrical connection with the contact 20. This thermostatic control of the contacts is similar to certain other devices employed in connection with previous constructions.

According to the present invention however the said contacts are adapted when closed to short-circuit the heating element of the iron, thus causing an increased flow of current in the circuit which results in such circuit being opened by the cut-out. This short-circuiting may be effected either 75 directly as by connecting the contacts 19 and 20 one with the terminal 21 of the iron and the other with the terminal 23 of such iron, or in cases where the voltage of the circuit is such as to render a direct short-circuit objectionable, one of such contacts may be connected with its corresponding terminal through a suitable resistance as 80 22 which will be less than that of the resistance of the heating element. 85

This arrangement necessitates no structural alteration to the iron beyond the addition thereto of the thermostat with its contacts and resistance 22 and the necessary connections to the terminals 21 and 23 and consequently the ordinary two-wire cord 24 and its plug 25 will serve for connecting the iron to the circuit. 90

The cut-out will preferably be mounted upon a wall or other fixed point and the customary wall plug 27 may be employed to connect the flexible cord 24 with the circuit. The usual switch 28 may also be employed in the circuit for the purpose of switching the current on and off as customary. 100

In operation the current being switched on and the switch of the cut-out having been closed by manipulation of the knob 10 so as to place the cut-out in the condition shown in full lines Fig. 2 the current from the circuit 2 will flow through the element 3, thus heating the iron in the usual customary manner. The current will of course flow through the winding 6 but will not energize the latter sufficiently to raise the core 7 while such winding being of low resistance will have practically no effect upon the flow of current to the element. 110

Upon the temperature of the iron rising above a predetermined degree however the thermostat will cause the contacts 19 and 20 to establish electrical connection with the result that the element 3 will be short-circuited either directly or through the lower resistance 22 as the case may be, thereby permitting an increased current to flow through the coil 6 which will in consequence raise the core 7 and so open the switch 4. 115

The switch 4 may be again closed by manipulation of the knob 10 but if this is ef- 120

fected before the temperature of the iron has fallen to an allowable degree the cut-out will again operate and open the circuit upon the arm 13 resuming its connection 5 with the contact 15.

From the foregoing description therefore it will be understood that the present invention not only serves to open the circuit upon the temperature of the iron rising 10 above a predetermined degree but also renders it impossible for any one to maintain the circuit closed until the temperature of the iron has fallen below such predetermined limit.

15 I claim:

1. In a device of the class described, the combination of an electric circuit, a switch in said circuit, a heating element and an electromagnet connected in series in said 20 circuit, said magnet being adapted when energized to operate said switch thereby to open the circuit, a thermostatic device disposed adjacent to said heating element and adapted to short circuit the same and increase 25 the current through said electromagnet thereby to energize the same, said switch being adapted to remain open after the magnet is deenergized, and manually operated means for operating the switch thereby 30 to close the circuit.

2. In a device of the class described, the combination of an electric circuit, a switch in said circuit, a heating element and an electromagnet connected in series in said 35 circuit, said magnet being adapted when energized to operate said switch thereby to open the circuit, a thermostatic device disposed adjacent to said heating element and adapted to short circuit the same, a resistance 40 element of lower resistance than said heating element in series with said thermostatic device and electromagnet whereby when the heating element is short circuited the current through said electromagnet is increased 45 thereby to energize the same, and

manually operated means for operating the switch thereby to close the circuit.

3. In a device of the class described, the combination of an electric circuit, a switch in said circuit, a heating element and an 50 electromagnet connected in series in said circuit, said magnet being adapted when energized to operate said switch thereby to open the circuit, a thermostatic device disposed adjacent to said heating element and 55 adapted to short circuit the same and increase the current through said electromagnet thereby to energize the same, a second switch in said circuit, and manually operated means for closing the first switch, said 60 manually operated means being adapted to open said second switch when moved into position to close the first switch.

4. In a device of the class described, the combination of an electric circuit, a switch 65 in said circuit, a heating element and an electromagnet connected in series in said circuit, said magnet being adapted when energized to operate said switch thereby to open the circuit, a thermostatic device disposed adjacent to said heating element and adapted to short circuit the same and to increase 70 the current through said electromagnet thereby to energize the same, manually operable means for closing said switch, 75 a second switch in said circuit and having a movable member, and means connecting said movable member with said manually operable means, said connecting means being adapted to normally retain said second 80 switch closed and to open the same when the manually operable means is moved into position to close the first switch.

In testimony whereof I affix my signature in presence of two witnesses.

CHARLES ADAMS SIMPSON.
